Primary Examiner — Kendra Leslie Hamilton*Assistant Examiner* — Amanda Christensen*(74) Attorney, Agent, or Firm* — Georgi Korobanov(57) **CLAIM**

The ornamental design for portable power station, as shown and described.

DESCRIPTION

FIG. 1 is a front view of a portable power station, showing my new design;

FIG. 2 is an enlarged front view of the detail identified in FIG. 1;

FIG. 3 is a rear view of the portable power station;

FIG. 4 is a left side view thereof;

FIG. 5 is a right side view thereof;

FIG. 6 is a top view thereof;

FIG. 7 is a bottom view thereof;

FIG. 8 is a top, rear, right side perspective view thereof; and,

FIG. 9 is a top, front, left side perspective view thereof. The broken lines in the drawings depict portions of the portable power station that form no part of the claimed design.
